[57] CLAIM

The ornamental design for a portable hand held bagger, as shown and described.

DESCRIPTION

FIG. 1 is a perspective view taken from the top, front and right side of a portable hand held bagger showing my new design;

FIG. 2 is a front elevational view thereof;

FIG. 3 is a right side elevational view thereof, the left side being a mirror image of the right side shown;

FIG. 4 is a rear elevational view thereof;

FIG. 5 is a top plan view thereof; and

FIG. 6 is a bottom plan view thereof.

The broken line representation of a trash bag, trash and a trash bag holding rope in FIG. 1 is for purposes of illustration only and forms no part of the claimed design.
